UNITED STATES PATENT OFFICE

2,383,518

CONNECTION BOX FOR ELECTRICAL TERMINALS

Rudolph I. Schonitzer, Shaker Heights, and Edwin L. Allen and Harold B. Muster, Cleveland Heights, Ohio; said Allen and said Muster assignors to said Schonitzer

Original application February 23, 1942, Serial No. 432,006, now Patent No. 2,359,053, dated September 26, 1944. Divided and this application December 30, 1943, Serial No. 516,143

9 Claims. (Cl. 248—346)

The invention relates generally to a novel and improved connection box assembly for use in electric power distribution. It particularly relates to an assembly of this nature for housing terminals whereby a plurality of subordinate power circuits are tapped off from a main circuit.

The object of the invention is to provide a connection box which is moisture-tight and weatherproof, but which can be constructed more rapidly and cheaply, and from lighter weight material than connection boxes now available.

Another object of the invention is to provide a box assembly of the nature indicated which is characterized by improved mechanical properties as a result of the structural features to be described hereinbelow.

Further objects and advantages will be apparent from a description of one embodiment of the invention, illustrated in the accompanying drawing, in which

Fig. 1 is a top plan view, partially broken away, of a connection or outlet box assembly embodying the inventive features now to be described.

Fig. 2 is a section taken on the line 2—2 of Fig. 1.

Fig. 3 is a side elevation of the assembly partially broken away, as seen from the right of Fig. 2.

Fig. 4 is a fragmentary top plan view of one corner of a box and associated base member, representing a somewhat modified embodiment of the invention.

Fig. 5 is a section taken on the line 5—5 of Fig. 4, looking in the direction of the arrows.

Fig. 6 is a fragmentary side elevation of a box and associated base member, representing yet another modification of the invention.

Fig. 7 is a section taken on the line 7—7 of Fig. 6, looking in the direction of the arrows.

Before the present invention is described in detail it is to be understood that such invention is not limited to the details of construction and/or the specific arrangement of parts herein illustrated and/or described, as the invention obviously may take other forms. It also is to be understood that the phraseology or terminology herein employed is for the purpose of description and not of limitation.

The connection box assembly representing the embodiment of the invention shown in Figs. 1, 2, and 3 comprises four main components identifiable as an outer cover 11, an inner cover 12, a box 13 and a base member 14. These members are preferably formed from a deep drawing type of low carbon, low manganese sheet steel by a

pressing or stamping operation, but obviously any type of sheet metal of adequate physical properties may be used, provided it is ductile enough to withstand the amount of deformation required by the structural design.

As seen in Figs. 1, 2, and 3, the box 13 is of substantially rectangular sectional contour in all three dimensional planes, though slightly rounded at the meeting zones of the vertical walls with each other and with the bottom wall, as a matter of practical convenience in facilitating the forming operation. Around its upper edge portion the box wall is outturned to form a flange 15, which flange is further provided around its outer edge, with a downwardly opening channeled portion 16 which is peripherally continuous, though somewhat enlarged in lateral extent at spaced locations 17 to permit insertion of conventional clinch nuts 18 (Fig. 2) which are provided with threaded bores 19 for a purpose which will appear. The flange 15 and channel 16 in conjunction provide an upwardly stepped contour.

A stamped metal band 20 is inserted within, and in circumferential contact with, the upper portions of the box walls (Fig. 2), being attached thereto by welding or otherwise. The upper edge 21 of said band extends above horizontal flange 15, and is preferably crimped over to form a portion of double thickness, and to provide a spacing shoulder 22 for initial positioning of the band before welding. The depression or upwardly opening channel extending peripherally between the edge portion 21 and the neighboring stepped-up wall of channel 16 carries therein a filler strip or gasket 23 which, as will appear, cooperates with the inner cover member in providing a weatherproof sealing fit when the box assembly is closed.

Extending longitudinally of the interior of box 13 is a bridge member 24 which is conveniently formed from a metal stamping having at its mid section a slightly channeled contour comprising an upper planar portion 25, and downturned, lateral flanges 26. Near their ends, these flanges 26 are enlarged to form angular supporting wings 27 which, at their terminal extremities, are bent outwardly to form ears 28 which may be conveniently welded or otherwise attached to the inner surface of the box walls.

A strip or plate of electrically nonconducting material 29 is attached to the upper surface of bridge 24, and carries, near one end thereof, two connections 30 and 31, to which supply line terminals may be attached. In parallel therewith is

a double row of subordinate taps 32 and 33, connected respectively to terminals 30 and 31, and adapted to be used as leads for an appropriate number of subordinate circuits. Both the supply line inlets, and the distribution outlets are effected by the insertion of suitable conduits (not shown) through suitable apertures 34 in one or more of the box walls, the number and location of such apertures (two of which are indicated in dotted lines, Fig. 3) being determined by convenience or necessity, and, as a precaution against moisture, a conventional packing gland is inserted in each wall aperture around the conduit or conduits extending therethrough.

The inner cover member 12 resembles a shallow, downturned tray which is complementary to, and conforms in contour with, box 13. Its peripheral edge portion is upturned, as seen at 35 (Fig. 2), thereby presenting a rounded edge for pressure contact with the packing strip 23. This inner cover is leakproof or imperforate, so as to provide an airtight seal when closing pressure is applied in a manner now to be described.

The outer cover 11 is generally designed to overlie and bring pressure to bear upon the inner cover. It is accordingly similar in general contour to the inner cover, with some exceptions now to be detailed. Surrounding its outer edge is a peripheral step comprising a horizontal portion 36 and a vertical portion 37, this step overlying, and exteriorly surrounding the channel 16 on the flange of box 13 when the outer cover 11 is in closed position. At spaced locations in registry with the threaded bores 19 in clinch nuts 18 hereinabove described, the outer cover is provided with apertures 38 to receive the shanks of screws 39, said screws being threaded to fit bores 19.

The box and the inner and outer covers are assembled in airtight relationship as follows. The inner cover 12 is placed on the box 13 with the lower edge of the inner cover in peripheral registry and contact with gasket 23. The upper cover 11 is then superimposed upon the lower cover so that apertures 38 in the upper cover are in registry with apertures 19 in the clinch nuts carried by box 13. Screws 39 are then inserted through apertures 38 and into the threaded bores 19, and the screws are drawn up until the horizontal step portion 36 is in contact with the horizontal component of channel 16. This operation causes the peripheral edge of the inner cover 12 to be imbedded in gasket 23 sufficiently to make the enclosure airtight.

The base member 14 will now be described. It consists of an H-shaped member formed of sheet metal, comprising two end members, indicated generally by reference numeral 42, underlying the ends of box 13, and a connecting member 43 which is integral with the end members 42, and which underlies, longitudinally, the body of the box. Said end members project beyond the sides of the box, and are provided with upwardly directed wing portions 44 along their innermost edges, and with end flanges 45, also upwardly directed, and contacting the end walls of the box. The wings 44 have laterally extending, connecting tabs 46 which are disposed to lie in contact with the side walls of the box, and to be welded thereto as at 47 (Fig. 3), and the end flanges 45 in contact with the end walls of the box, may also be welded, or otherwise connected, to the box, as at 48. The four end parts of the end members 42 are perforated at 49, to permit insertion therethrough of the shanks of bolts,

studs, or other means whereby the assembly may be attached to a wall, ceiling, bulkhead, or other structural member.

The embodiments shown in Figs. 4, 5, 6 and 7 illustrate other means for securing the box assembly to a supporting structure. In some instances the outlet box may be so long that in the interests of metal conservation it may be desirable to eliminate the connecting member 43 of base 14. In such case (see Figs. 4 and 5), each end of the box is provided with a base bracket 50 which is placed transversely beneath each end of box 13 and projects laterally therefrom a sufficient distance to provide upturned wings 51 and end flanges 52. Flanges 52 are welded to the ends of box 13 as previously described in connection with the first embodiment, and connecting tabs 53 are carried by wings 51 for attachment to the side walls of box 13. In this embodiment a portion of the bottom of the box may be raised slightly as at 54, to permit the general box bottom to be in coplanar registry with the base brackets 50.

Additional support may likewise be provided at spaced locations along the length of box 13 (Figs. 6 and 7) by cross brackets 55 which run transversely beneath the box, projecting laterally therebeyond at each end to provide wings 56 and connecting tabs 57, the function of each being now familiar. The horizontal portions of the projecting ends of brackets 50 and 55 are provided with apertures 58 for convenience of attachment as aforesaid. In the use of bracket 55, the bottom of box 13 may be slightly raised in the neighborhood of the bracket (see Fig. 6), to avoid projection of the bracket below the level of the box bottom.

If desired the outer cover 11 may be provided with a raised escutcheon portion 60 which carries a name plate 61 or device of similar character. In such case, said cover may be provided with inwardly upset, annular apertures, sufficient metal being thus provided, as at 62 (Fig. 2) to carry a thread for screws 63 which serves to retain the name plate in place.

The assembly, constructed as described, may be fabricated and assembled both rapidly and economically, using only a minimum amount of metal. A number of factors contribute to supply adequate structural properties, including the flange 15 and channel 16 which, in conjunction, constitute a peripheral strengthening step; the band 20 and its reinforced edge 21; the bridge member 24; the upturned edge of the inner cover; the stepped edge of the outer cover, and the wing-strengthened base, all of which features cooperate to afford a strength and rigidity which is more than adequate. The enclosure is sufficiently weathertight to protect the various electrical terminals and taps against corrosion, and is therefore particularly suitable where corrosive atmospheres may be encountered, for instance in ships, in installations near the ocean, or under familiar industrial conditions.

The present application is a division of our copending application for Connection boxes for electrical terminals, filed February 23, 1942, Serial No. 432,006, now Patent No. 2,359,053, granted September 26, 1944.

What we claim is:

1. A base member for a box structure wherein said box structure has a bottom wall and a peripherally continuous upstanding wall, said base member being formed from sheet metal and having a portion thereof underlying and connected

to the bottom wall of said box structure and having another portion thereof projecting beyond the bottom wall of said box structure, said projecting portion having upturned wing means for attachment to the upstanding wall of said box structure, and said projecting portion also having laterally extending means for the securement of said base member to a supporting structure.

2. A base member for a box structure wherein said box structure has a bottom wall and a peripherally continuous upstanding wall, said base member being formed from sheet metal and having a portion thereof underlying and connected to the bottom wall of said box structure and having another portion thereof projecting beyond the bottom wall of said box structure for securement to a supporting structure, said projecting portion having means integral therewith and extending upwardly along opposed portions of said peripherally continuous upstanding wall for attachment thereto, and said projecting portion having further means, likewise integral therewith, and extending upwardly along other opposed portions of said peripherally continuous upstanding wall, likewise for attachment thereto.

3. A base member for a box structure wherein said box structure has a bottom wall and a peripherally continuous upstanding wall, said base member being formed from sheet metal and having a portion thereof underlying and connected to the bottom wall of said box structure and having another portion thereof projecting beyond the bottom wall of said box structure, said projecting portion having perforated tab means for attaching said base member to a supporting structure and having wing means, upturned from said tab means, for the securement of said base member to the upstanding side wall of said box structure.

4. A base member for a box structure wherein said box structure has a bottom wall and a peripherally continuous upstanding wall, said base member being formed from sheet metal and having a portion thereof underlying and connected to the bottom wall of said box structure and having another portion thereof projecting beyond the bottom wall of said box structure, said projecting portion having perforated tab means for attaching said base member to a supporting structure and having flanged wing means upturned from said tab means, for the securement of said base member to said upstanding wall, and said projecting portion having upwardly extending end flanges for additional securement of said base member to the upstanding side wall of said box structure.

5. A base member for a box structure wherein said box structure has a bottom wall and a peripherally continuous upstanding wall, and wherein said bottom wall is provided with a portion indented out of the general plane of said bottom wall, said base member being formed from sheet metal and having a portion thereof underlying said bottom wall and complimentary to said indented portion of said bottom wall so as to lie therein, said base member having a portion thereof projecting beyond the bottom wall of said box structure, said projecting portion having means for attaching said base member to a supporting structure and having additional means

for the securement of said base member to the upstanding side wall of said box structure.

6. A base member for a box structure wherein said box structure has a bottom wall and a peripherally continuous upstanding wall, and wherein said bottom wall is provided with a centrally located elongated portion indented out of the general plane of said bottom wall, said base member being formed from sheet metal and having a portion thereof underlying said bottom wall and complimentary to said indented portion of said bottom wall so as to lie therein, said base member having a portion thereof projecting beyond the bottom wall of said box structure, said projecting portion having means for attaching said base member to a supporting structure and having additional means for the securement of said base member to the upstanding side wall of said box structure.

7. A base member for a box structure wherein said box structure has a bottom wall and a peripherally continuous upstanding wall, and wherein said bottom wall is provided with an edge portion indented out of the general plane of said bottom wall, said base member being formed from sheet metal and having a portion thereof underlying said bottom wall and complimentary to said indented portion of said bottom wall so as to lie therein, said base member having a portion thereof projecting beyond the bottom wall of said box structure, said projecting portion having means for attaching said base member to a supporting structure and having additional means for the securement of said base member to the upstanding side wall of said box structure.

8. A base member for a box structure wherein said box structure has a bottom wall and a peripherally continuous upstanding wall, said base member being formed from sheet metal and having a portion underlying and connected to the bottom wall of said box structure, said base member also being provided adjacent each of the two ends of its first mentioned portion with a pair of oppositely extending portions projecting laterally beyond the bottom wall of the box structure, the base member being therefore of substantially H form in plan view, at least one of the four projecting portions of the base member having means for the attachment of the base member to a support and at least one of said projecting portions having additional means connected to the upstanding wall of said box structure.

9. A base structure for a box structure wherein the box structure has a bottom wall and a peripherally continuously upstanding wall having opposed side wall parts and opposed end wall parts, said base structure having two portions underlying and connected to the box structure bottom wall, one adjacent each end wall part of the box structure's upstanding wall, each of said portions of said base structure projecting laterally beyond the opposed side wall parts of the upstanding wall of the box structure and being provided outwardly of said side wall parts with upstanding flanges connected thereto, and each of said portions being provided with other upstanding flanges outwardly of said end wall parts and connected thereto.
